CLOTH-CUTTING MACHINE

William Bangser, New York, N. Y., assignor to
 H. Maimin Company, Incorporated, a corpora-
 tion of New York

Application July 4, 1945, Serial No. 603,153

2 Claims. (Cl. 51—249)

1

This invention relates to cloth-cutting machines of the reciprocating knife type and particularly to means for sharpening the knives of such machines.

In my Patent No. 2,156,798, I have illustrated and described a motor-driven cloth-cutting machine of the reciprocating knife type provided with a pair of rotary grindstones for periodically sharpening the knife. While the machine is being used for cutting cloth, the stones, carried on swinging arms, mounted in a vertically reciprocating slide, are held forward of the knife guard, well above and beyond the upper end of the knife. When the time for sharpening comes, the guard and presser foot are lowered and a friction drive wheel is swung into contact with the fly wheel of the motor, whereupon, through appropriate mechanism the stones, rotating on vertical axes, are swung on their arms around the guard and into grinding contact with the knife, one on either side. While the stones are still rotating (outwardly with respect to the cutting edge) the slide on which they are mounted is moved down the length of the reciprocating knife and up again, whereupon the stones are swung out by the same means that swung them in, and into inoperative position, thus completing the grinding cycle.

This machine has performed its intended function efficiently and well. Under certain circumstances, however, the operation has been found to be less than perfect, and it is the object of the present invention to eliminate these imperfections.

The means shown in my patent for swinging the stones into and out of grinding contact with the knife comprises spindles about which the stone arms swing, movable with the stones and provided with threads of large pitch which engage nuts of like pitch fixed to the frame of the machine. It has been found that, under the vibration of operation, a stone may swing slightly out of its proper position toward the end of the grinding cycle so that the upper end of its threaded spindle engages its nut with the threads out of alinement. This immediately jams the machine. In accordance with the present invention I have provided helical cams of such configuration that no matter how far out of position a stone may vibrate—within the limits imposed by the machine itself—the fixed and movable cams will cooperate to swing the stone to its prearranged position of rest without possibility of jamming.

It has also been found that the grinding mechanism, under the vibrations set up by the cloth-cutting operation, has a tendency to creep. This

2

is because, when the friction drive wheel is moved out of contact with the fly wheel at the end of the grinding cycle, the movement of the grinding mechanism stops instantly, leaving only a very small clearance between the two wheels. The grinding cycle cannot be initiated while the presser foot is elevated above the base of the machine because a safety arm, swingable with the friction drive-wheel, engages the guard when the presser foot is elevated and so prevents the drive wheel from making driving engagement with the rotating fly wheel. As the presser foot and guard are always raised during cloth-cutting, creeping of the grinding mechanism cannot accidentally initiate the grinding cycle at that time; nevertheless, this creeping causes the safety arm to press against the guard and binds it in its guideways so that it cannot be raised and lowered as it frequently must be in normal operation. In accordance with the present invention, I have provided means for positively latching the reciprocating grinder slide in its upper or inoperative position so that the mechanism cannot creep far enough to bind the guard.

In the accompanying drawings I have illustrated certain preferred embodiments of my invention, although others could doubtless be devised within its purview, as defined by the appended claims. In these drawings,

Figure 1 is a side elevation of a cloth-cutting machine of the reciprocating knife type,

Figure 2 is a fragmentary vertical section on an enlarged scale taken along line 2—2 of Figure 1,

Figure 3 is a vertical section taken along line 3—3 of Figure 4,

Figure 4 is a vertical section taken along line 4—4 of Figure 3,

Figure 5 is a fragmentary front elevation showing the grinder slide latch,

Figure 6 is a horizontal section taken along line 6—6 of Figure 5,

Figure 7 is an end view of the latch shown in Figure 5,

Figures 8, 9, 10 and 11 are perspective views of the right hand helical cams, and

Figures 12 and 13 are transverse sections taken along lines 12 and 13 respectively.

Except for the helical cams and the grinder slide latch of the present invention and the gear shift mechanism, the machine illustrated in these drawings is essentially the one illustrated in Figures 1 through 9 of Patent No. 2,156,798, to which the reader should refer for a more detailed account of the machine and its operation, a knowl-

edge of which will be generally presumed in the description to follow.

The cloth-cutting machine illustrated in these drawings comprises the usual base 1 on which is mounted a standard 2 carrying a motor 3. A knife 4 is mounted in a vertical slot in the forward edge of the standard and reciprocated by means of a cross-head 5, a pitman 6 and a crank 7, mounted on the fly wheel 8 of the motor. A guard 9 carrying a presser foot 11 is mounted for vertical adjustment immediately in front of the knife. Mounted on the front of the motor housing is a fixed grinder frame 12 having vertical guideways 13 in which is slidably mounted a grinder slide 14 closed at its lower end by a block 15 extending inward. Journalled in the inner end of this block are two vertical spindles 16 supporting at their lower ends arms 17 carrying studs 18 on which grindstones 19 are journalled. The upper ends of the spindles 16 terminate in pilot rods 21 enveloped by and carrying cams 22 adapted to engage fixed cams 23 carried by the fixed grinder frame 12 to swing the stones 19 into and out of grinding contact with the knife as the grinder slide is traversed, substantially as described in Patent No. 2,156,798. Coil springs 24 encircle the cams 22, being anchored at one end to the block 15 and at the other to one of the cams 22, and tend to swing the stones into grinding contact with the knife.

The shaft 25, which carries the friction drive wheel 26, is journalled in a sleeve 27 pivoted at 28 to the fixed grinder frame 12 for movement of the drive wheel in a vertical plane and is also journalled at the end remote from the drive wheel in a block 29 likewise pivoted at 28 to the frame. A trigger arm 30 is pivoted at 31 to the lower face of the block 29 for movement in a horizontal plane. During the cloth-cutting operations of the machine the trigger arm 30 is held in a horizontal position parallel with the grinder slide 14 by means of a bracket 32 projecting from the forward face of the slide and in this position, as illustrated in Figure 5, the friction drive wheel 26 is held out of contact with the fly wheel 8. A coil spring 33, supported at one end upon a bracket 34, which extends laterally from the fixed grinder frame 12, engages the pivoted block 29 at its other end, and tends to swing the block clockwise about the pivot 28 to hold the friction drive wheel 26 in driving engagement with the fly wheel 8. As long, however, as the trigger arm 30 is held in horizontal position by the bracket 32, the spring 33 is held under compression and cannot act to swing the friction drive wheel into driving position. In order to initiate the grinding cycle, the operator seizes the trigger arm 30 and swings it forward about its pivot 31 against the compression of a spring 35 which normally holds the trigger parallel to the grinder head 14. When the trigger has cleared the bracket 32, the spring 33 is free to act and does act to swing the friction drive wheel into engagement with the fly wheel. At the same time a cam 38 depending from the trigger arm 30 withdraws a slide latch 36 from an opening 37 in the grinder slide 14 where it is normally held under pressure of a spring 40, and this frees the slide for the grinding traverse, which immediately follows.

At the end of the shaft 25 remote from the friction drive wheel 26 there is fixed a pinion 39 which meshes with a gear 41 coaxial with a pinion 42 meshing with a gear 43 which, in turn, drives a pinion 44 meshing with a gear 45 integral with a bevelled pinion 46 which drives a second

bevelled pinion 47 through which passes a vertical square drive shaft 48 journalled in the grinder slide 14. Fixed to the lower end of the square shaft 48 and just below the lower face of the block 15 is a gear 49 which meshes with a pinion 51 coaxial with the spindle 16 which pinion in turn meshes with a gear 52 carried by one of the grindstones 19. A similar gear train rotates the other grindstone through the intermediary of an idler 53 mounted on the lower face of the block 15. When friction drive wheel 26 is swung into engagement with the rotating fly wheel 8 of the motor, the gear trains described above are set into operation to rotate the grindstones 19. The gears 39 through 47 are mounted upon the fixed grinder frame 12, whereas the gears 49 through 52 and 53 are carried by the grinder slide 14 and move with it. The square shaft 48 which makes a sliding engagement with the bevelled pinion 47 and extends the entire length of the grinder slide 14, drives the second gear train throughout the grinding traverse and in all positions of the grinder slide.

The grinder slide 14 is traversed as follows: Two sprockets 75 are mounted upon the grinder frame 12 and about these runs a chain 76, one link of which carries a roller 77 lying within a horizontal slot 78 in a plate 79 fixed to the upper end of the grinder slide 14. Movement of chain 76, therefore, reciprocates the slide. The chain is driven through a pinion 81 fixed to gear 43 and meshing with a gear 82 and the lower sprocket shaft.

The pinion 44 is rotatably mounted on a spindle 54 carried by a link 55 mounted for limited oscillation about a spindle 56 on which the combination spur and bevelled gears 45, 46 are journalled and made to mesh either with driving gears 43 or 59, the latter carried by gear 61 which, in turn, is driven by gear 41. A gear shift lever 62 is pivotally connected at its inner end to spindle 54, which carries the pinion 44, so that the operator, by seizing the knurled end of the shift lever and properly manipulating it, may move the pinion 44 from the low speed position shown, where it meshes with gear 43 to the high speed position where it meshes with pinion 59. In this way the rotary speeds of the stones may be varied. As this gear shift forms no part of the present invention, I shall not describe it further.

The cams 22 and 23, as shown most particularly in Figures 8 through 13, are so designed that no matter how far the movable cam 22 may be displaced—within the limits imposed by the machine—it will always engage the fixed cam 23 in such a way as to swing its stone into its proper position of rest. The helical cams of each engaging pair are complementary, being semi-cylindrical at their bases and tapering toward their outer ends. The rear faces of both cams are provided with bulges 22a and 23a respectively which act to guide the cam 22 back into proper engagement with cam 23 should the former, by any chance, swing too far out of line. The cams can thus operatively engage through a wide arc of displacement.

Fixed to the sleeve 27 in which the shaft 25 of the friction drive wheel 26 is journalled, is an arm 84 pivoted at 28 and extending upwardly and inwardly, as illustrated in Figures 2 and 5, terminating in a set screw 85. This safety arm 84 lies within the vertical plane of the presser foot guard 9. When the friction drive wheel 26 is in its inoperative position, as shown in the

drawings, set screw 85 is out of engagement with the presser foot. When, however, the drive wheel 26 is swung toward engagement with the fly wheel, the set screw 85 would engage the guard if in elevated position, and thus prevent driving contact being made. It is, therefore, necessary for the operator first to lower the presser foot so as to carry the upper end of the guard below the arc described by the set screw 85. As explained above, however, the mechanism has a tendency to creep. If not prevented by the latch 36, this creeping motion would bring the set screw 85 into engagement with the elevated guard and exert sufficient pressure to bind and prevent manipulation of it by the operator.

I shall now describe briefly the operation of the machine throughout one grinding cycle. The operator first lowers the presser foot to move the guard below the arc described by the set screw on the safety arm 84, and an appropriate switch is closed to set the motor in operation. The operator then seizes the trigger arm 30 and pulls it forward out of engagement with the bracket at 32; whereupon the spring 33 swings the friction wheel 26 into engagement with the fly wheel 8, the cam 38 withdraws the latch 36 from the hole 37 in the slide 14 which immediately begins its downward movement while the grindstones 19 are swung around the guard and into grinding engagement with the knife due to the action of the springs 24 and the cams 22 and 23. On the return movement as the slide approaches the upper end of its traverse, the pilot rods 21 are received by the fixed cams 23 and guide the lower cams 22 into engagement therewith. Further upward movement of the slide, therefore, causes the spindles 16 to swing so as to carry the grindstones 19 around the guard and into inoperative position. Toward the end of the return movement of the slide, the bracket 32 engages the trigger arm 30, which has been swung inward by spring 35, and moves it into horizontal position against the pressure of spring 33. This swings the friction drive wheel out of engagement with the fly wheel and at the same time raises cam 38 permitting the spring 49 to swing the latch 36 back into the hole 37 to latch the slide as it reaches its upper position, thus ending the grinding cycle.

I claim:

1. In a cloth-cutting machine of the reciprocating knife type, the combination of a slide movable relative to the knife, a pair of spindles carried by the slide and terminating at their upper ends in pilot rods, swinging arms fixed to the spindles, stones for sharpening the knife mounted on the arms, a helical cam carried by each pilot rod, fixed helical cams on the machine adapted to receive the pilot rods and with which the movable helical cams engage when the slide is at or near its upper position, the helical cams of each pair being complementary, semi-cylindrical at their bases, tapering toward their outer ends, and with guiding bulges on their rear faces whereby they may operatively engage through a wide arc and means for moving the slide vertically relative to the knife, whereby engagement of the fixed and movable cams swing the stones relative to the knife.
2. In a cloth-cutting machine of the reciprocating knife type, the combination of a slide movable relative to the knife, a pair of spindles carried by the slide, swinging arms fixed to the spindles, stones for sharpening the knife mounted on the arms, a helical cam carried by each spindle, fixed helical cams on the machine with which the movable helical cams engage when the slide is at or near its upper position, the helical cams of each engaging pair being complementary, semi-cylindrical at their bases tapering toward their outer ends, and with guiding bulges on the rear faces and means for moving the slide vertically relative to the knife, whereby engagement of the fixed and movable cams swing the stones relative to the knife.

WILLIAM BANGSER.
